UNITED STATES PATENT OFFICE.

BERTON I. RIKE, OF DAYTON, OHIO, ASSIGNOR TO THE RIKE FOLDING BOX COMPANY,
OF DAYTON, OHIO, A CORPORATION OF OHIO.

BAG.

1,184,876.

Specification of Letters Patent. Patented May 30, 1916.

Application filed January 21, 1915. Serial No. 3,453.

To all whom it may concern:

Be it known that I, BERTON I. RIKE, a citizen of the United States, residing at Dayton, in the county of Montgomery and State 5 of Ohio, have invented certain new and useful Improvements in Bags, of which the following is a specification, reference being had therein to the accompanying drawing.

This invention relates to bags and more 10 particularly to bags such as are used for storing garments and the like.

The object of the invention is to provide a bag of this kind which will be light and inexpensive in its construction; which 15 can be folded into a compact package; which will have a tight, easily operated closure; and which will be provided with means for supporting the contents of the bag independently of the bag so as to relieve the 20 walls of the bag of the strain which is imposed thereon when the contents of the bag are supported by the bag itself.

To this end it is a further object of the invention to provide the open end of the 25 bag with flaps adapted to fold across the opening and coöperating to tightly close the same; to so construct the flaps that when not in use they will lie flat and substantially parallel with the side walls of the bag, 30 thereby enabling the bag to be folded into a flat compact bundle.

A further object of the invention is to provide a hanger which will support the bag itself and will support the contents of the 35 bag independently of the bag, thereby relieving the walls of the bag from all strain which would tend to injure the same and distort the closure for the opening, and enabling the bag to be made of lighter material which is not only less expensive but 40 renders the bag easier to handle and enables it to be folded into a more compact bundle than where made of heavy material.

In the accompanying drawings, Figure 1 45 is a perspective view of the upper portion of the bag with the opening partly extended and showing my invention applied thereto; Fig. 2 is a sectional view taken on the line xx of Fig. 1 and looking in the direction of 50 the arrows; and Fig. 3 is a transverse, sectional view showing the opening closed.

In these drawings I have illustrated one embodiment of my invention and have shown the same as applied to a bag, the upper por-

tion of which is indicated at 1 and which 55 comprises side walls which, when the bag is empty, extend substantially parallel one with the other and are attached one to the other at their lateral edges and at one end, preferably by overlapping the edges and 60 pasting them together, although the connection may be made in any suitable manner. The edges of the side walls at the other end of the bag are unattached and an opening 65 is thus provided for the insertion and removal of articles. The edges of the side walls adjacent to the opening are reinforced and are provided with coöperating flaps forming a closure therefor, these flaps being arranged to fold across the opening 70 and to fold one upon the other to form a tight closure for the opening. In that form of the invention here illustrated I have combined the closure with a reinforcement 75 for the edges of the opening. As here shown I have secured to the side walls of 80 the bag, along the edges of the opening, reinforcing strips 2 and 3, of card-board or extra heavy tough paper. These strips may be secured to the bag in any suitable manner, as by pasting, and, in the present instance, there are two of the strips, one on each side of the opening, and they are provided with overlapping ends to reinforce 85 the ends of the opening. As here shown one of the strips, 2, is of greater length than the bag and its end portions 4 are bent about the lateral edges of the bag and folded on and pasted to the adjacent ends of the reinforcing strip 3. This reinforcement not 90 only protects the edges of the walls from being torn but tends to support the edges of the bag when the opening is distended, so as to permit articles to be readily inserted 95 therein. The reinforcing strip 2, which is secured to the rear wall of the bag, as shown in Fig. 1, has a portion projecting above the adjacent edge of the bag for substantially the full width of the bag, as shown at 5. This projecting portion of the reinforcing strip constitutes one flap of the closure for the bag and is adapted to be folded across the open end of the bag and down against the front reinforcing strip 3, as shown in Fig. 3, the reinforcing strip 2 being 100 scored along a line adjacent to and substantially parallel with the upper edge of the bag to facilitate the folding of the flap.

across the opening. The reinforcing strip 3 is provided at that edge farthest removed from the opening with a projecting portion 6 which normally extends downwardly parallel with the side wall of the bag and is scored lengthwise of the strip to enable it to be folded upward against the downwardly folded flap 5. Thus the flap 5 extends across the opening and effectually closes the same, and the flap 6 is folded over the edge of the flap 5 and not only holds this flap down against the bag but incloses the edge thereof and prevents the entrance of dust or vermin which might work their way about a single flap.

Suitable means are provided for holding the flaps in their folded positions to maintain the bag snugly closed. Various devices may be used for this purpose but I have found that here shown to be very efficient. This fastening device comprises a series of clips 7 which are preferably formed from flexible metal, such as tin, each having one end extending between the reinforcing strip 3 and the side wall of the bag and secured to the reinforcing strip, by means of prongs 8, or in any other suitable manner. The free ends of the strips extend downward between the flap 6 and the wall of the bag and project some distance beyond the edge of the flap. When the flaps are in their folded positions the clips are bent upward in snug contact with the flap 6 and their upper ends are carried across the end of the bag and bent downward against the reinforcing strip 2, thereby clamping the closure firmly in its closed position and preventing the same from gapping or becoming loosened by handling.

I have also provided means for supporting the garments or other articles within the bag independently of the bag itself. Where the contents of the bag are supported by the walls of the bag there is not only danger of the paper tearing under the weight imposed upon it but there is a tendency to distort the closure. I avoid these objectionable features by providing a hanger which extends through one wall of the bag and engages the same to support the bag and which has on the inner side of the bag a portion designed to support the garments, or the like, and has at its outer end a portion designed to support both the bag and the contents of the bag. In the particular construction here illustrated this hanger comprises a rod or heavy wire having at its outer end a hook-shaped portion 9 adapted to support the hanger and the various articles carried thereby. This rod extends through an opening 10 formed in the rear wall of the bag and in the reinforcing strip 2 and is bent upward, as shown at 11, just inside of the opening to form a seat which engages the reinforcing strip and forms a

support for the bag. This inner portion of the rod or hanger then extends downward and is bent at its lower end to form a hook 12 adapted to be engaged by and support a garment hanger 13 or to support the contents of the bag in any suitable manner. Thus, it will be apparent that the entire weight of the garments or other contents of the bag is carried by the hanger and none of it is imposed upon the bag itself, and that the same hanger which carries the garments also forms a support for the bag. Further, it will be noted that this hanger is comparatively flat in its construction and adds little to the thickness or bulk of the bag when the latter has been folded for shipment or storage.

It will be apparent from the foregoing description that I have provided a bag which not only has a very tight closure, is easy to operate and can be applied to the bag at a low cost, but that I have provided the bag with means for supporting its contents independently of the walls of the bag, thereby relieving the bag from the strain which would otherwise be imposed thereon and which would tend to tear the walls and distort the closure. Further, it will be apparent that the whole construction is such that the bag can be folded into a flat, compact bundle for shipment or storage. In this connection it will be noted that the hanger may be rotated in the opening 10 to cause it to extend substantially parallel with the edge of the bag and to lie within the bag so that it does not project beyond the edge of the folded bag. And further, it will be noted that the combined reinforcing strips and flaps lie flat and substantially parallel with the walls of the bag when they are in their open positions, and that the fastening devices for the closure likewise lie flat against the wall of the bag and have no projecting parts which would interfere with the folding of the bag into a compact bundle.

While I have shown and described one embodiment of my invention it will be understood that this has been chosen for the purposes of illustration and that I do not desire to be limited to the details of construction, for obvious modifications will occur to a person skilled in the art.

The subject-matter divided out of this case, and relating to the hanging hook and its relation to the other parts, is reserved to form the subject of another application.

Having thus fully described my invention, what I claim as new and desire to secure by Letters Patent is:

1. A bag having an opening at one end thereof, reinforcing strips secured to said bag along the edges of said opening, one of said strips having portions embracing the ends of the bag and overlapping the other

of said strips and a portion projecting beyond the end of the bag and adapted to be folded across said opening and against the other reinforcing strip, and said other reinforcing strip having a portion projecting beyond that edge thereof which is farthest removed from said opening and adapted to be folded against the projecting portion of the first-mentioned strip when that projecting portion is in its folded position, and clips embracing said flaps across the top of the bag.

2. The combination, with a bag having an opening in one end thereof, of a closure for said opening comprising a flap secured to said bag along one edge of said opening, projecting beyond said edge and adapted to fold across the opening and against the other edge thereof, and a second flap secured to said bag on a line spaced away from said other edge of said opening and adapted to fold upward against the first-mentioned flap, when the latter is in its folded position, and flexible clips secured to said bag and adapted to fold upward along said second flap, across the end

of the bag and down against the opposite side thereof.

3. A bag having an opening at one end thereof, reinforcing strips secured to said bag along the edges of said opening, one of said strips having a portion projecting beyond the end of the bag and adapted to be folded across said opening and against the other reinforcing strip and said other reinforcing strip having a portion projecting beyond that edge thereof which is farthest removed from said opening and adapted to be folded against the projecting portion of the first-mentioned strip when that projecting portion is in its folded position, and clips secured to said bag on one side of said opening and adapted to be bent across said flaps to retain the same in their closed positions.

In testimony whereof, I affix my signature in presence of two witnesses.

BERTON I. RIKE.
